UNITED STATES PATENT OFFICE.

ANTHONY AQUILA, OF ISELIN, NEW JERSEY.

CARD HOLDER.

Application filed November 12, 1926. Serial No. 147,928.

This invention relates to card holders and more particularly to devices of this character such as are employed for displaying price cards, single or in combination.

5 The primary object of this invention is to provide a novel and improved display card holder of a relatively simple construction adapted to be produced at low cost, yet, providing a most effective means for displaying 10 price cards and the like.

Another object is to provide a price card holder adapted to be readily clamped onto the edge of a shelf and detached therefrom, having adjustable means of a novel and improved construction.

15 A further object is to provide a device of the character specified where the figures or other indications printed on the cards carried thereby are arranged to show through 20 openings provided in a front plate, which also acts as a means for retaining said cards in position.

Other objects and advantages of the present invention will more fully appear as the 25 description proceeds and will be set forth and claimed in the appended claims.

My device comprises essentially a body or holder proper provided with means for receiving and holding the cards in position, 30 and a front member or plate detachably connected to said body adapted to retain said cards in position preventing lateral displacement thereof, said plate being provided with openings through which the figures or other 35 indications printed on the cards may be displayed.

A preferred embodiment of my invention is illustrated in the annexed drawings, in which:

40 Fig. 1 is a front view in elevation of my improved card holder;

Fig. 2 is a plan view of the same;

Fig. 3 is a side view in elevation of the same;

45 Fig. 4 is a side sectional view through line 4—4 of Fig. 1, showing the device clamped onto the edge of a shelf;

Fig. 5 is a plan sectional view of the same through line 5—5 of Fig. 1;

50 Fig. 6 is a rear view in elevation of the same;

Fig. 7 is a front view in elevation of the device showing a way of inserting and removing the front plate;

55 Fig. 8 is a side view in elevation of the device showing the same mounted onto the

edge of a shelf in a manner different from that illustrated in Fig. 4; and

Fig. 9 is a side view in elevation of the device illustrating the same placed upon a 60 counter in an inclined position.

My improved device comprises a body portion 10, made in the form of a plate having two opposite edges, preferably the upper and the lower edges, bent forwardly and inwardly to form retaining flanges 11, 12. Said flanges are spaced from the front or inner surface of the plate as shown at 13, a distance sufficient to receive the thickness of a display card 14, as well as the thickness of 70 a front plate or cover 15 which is in the present case slidably inserted in position from the right side in a superimposed relation to said display card or cards as Fig. 7 clearly shows.

75 The side at which the sliding cover 15 is inserted is unobstructed at the front affording a free and clear passage for said cover; the edge at said end or a substantial part thereof, is bent rearwardly and inwardly to 80 form a flange 16 at the rear, said flange being spaced from the rear surface of the body a distance corresponding to the thickness of a sliding clamping member 17, having a lateral extension 18 inserted between said flange 85 and the body of the device.

The edge at the opposite end of the body plate has its central portion extending for almost the entire length of the edge bent rearwardly and inwardly to form a flange 19 90 at the rear corresponding to flange 16 at the opposite end. Said flange 19 is also spaced from the rear surface of the body providing a clearance space through which lug 20 extending from the other end of clamping 95 member 17 may be inserted and retained.

In this manner flanges 18, 20 form two runways within which clamping member 17 may be slidably adjusted at any desired point. At one end, said clamping member is 100 provided with a cam locking member 21, pivotally mounted at 22, provided with a handle or projection 23 by means of which the cam member may be operated.

105 Referring to Fig. 6, where the cam member is illustrated in its locking position, it will be seen that if handle or projection 23 is forced downwardly causing angular movement of the cam member in a clockwise direction, the clamping member will be released and will be free to move up and down in its runways. Once, the new position is 110

reached the cam member may be rotated in the opposite direction until its surface will wedge against the edge of flange 18, securely locking the clamping member in position.

5 The remaining portions of the edge opposite to the side through which member 15 is inserted, that is, its upper and lower ends are bent forwardly and inwardly to form partial retaining flanges 24, 25, on a level 10 with flanges 11, 12, providing a stop for the cards inserted at the other end and slid in position between flanges 11, 12, and the body of the device.

15 Sliding member or cover 15, has the central portion of its inner end embossed as at 26, so as to be flush with the outer edges of flanges 24, 25, when part 15 is in its normal position shown in Fig. 1; furthermore, the outer end of said part 15, is embossed 20 throughout its entire length as at 27 to come flush with flanges 11, 12, so that when part 15 is in position flanges 11, 12, 24, 25, and embossed parts 26, 27, combine to provide the effect of a complete frame around the 25 front surface of part 15.

The outer end of part 15, furthermore has its edge bent rearwardly as at 28, so as to reach the front surface of the body plate 10, thus acting as a retaining means for the 30 outer end of card or cards inserted within said body plate. Plate 15 is provided with openings such as 29, 30, 31, 32, through which the figures or other indications printed on the cards may be displayed.

35 In this manner, a very effective display is obtained due to the contrast between the color of plate 15 and the color of the underlying card or cards and due to the fact that by restricting the field of the face color of 40 the card, the figures or other indications printed thereon will be set in evidence with greater intensity.

45 Embossed part 27 at one end of plate 15 completes the appearance of the frame provided by flanges 11, 12, 24, 25 and by embossed portion 26, and at the same time provides a shoulder or projecting portion against which the thumb may be applied to 50 force cover 15 outwardly when a change of cards is to be effected.

By virtue of this arrangement it will be observed that the card or cards may be inserted sidewise through the slotted passage 55 between flanges 11 and 12 and the body of the device, until the inner edge strikes the sides of flanges 24, 25; cover 15 may then be inserted through the same slotted passage in a superimposed relation to the card or cards and may be forced inwardly until its inner 60 edge registers with the inner edge of the card or cards, its embossed portion 27 coming to occupy the position shown in Fig. 1.

The cards used therefore, need not be bent or otherwise distorted in order to be placed 65 in position or removed therefrom and this

condition greatly favors the length of their useful life. This condition is also advantageous in this, that it permits the use of very smooth or glazed cardboard which would be apt to crease if the cards had to 70 be bent or distorted in order to be inserted in position or removed therefrom; and this in its turn may at times be preferable because printed matter stands up more effectively on highly glazed papers than on 75 papers having a matt surface.

At the rear, the device is provided with suitable supporting or attaching means, for instance, clamping means of the character shown. These consist of two rearwardly 80 directed flanges 33, 34, which are spaced at the proper distance to permit the insertion of the device over the edge of a shelf such as 35. Said flanges are preferably made of springy sheet metal providing some resiliency in the flanges themselves in order to 85 permit small variations in the thickness of the shelf and in order to exert a better clamping action.

However, in the preferred form, as stated, 90 one of the clamping flanges is adjustable, clamping flange 34 being in this case, made integral with sliding member 17 and projecting rearwardly therefrom. Clamping flange 33 is stationary being permanently 95 attached to the rear of body plate 13 in any suitable manner. The clamping flanges are preferably provided with longitudinally embossed inwardly projecting beads or depressions such as 36, 37, insuring a positive line 100 of contact between the flanges and the surfaces against which they abut.

By virtue of the construction described, the distance between the two clamping flanges may be adjusted at will so that the 105 device may be attached onto shelves of various thicknesses. In some cases, however, it is not possible or convenient to have the flange projecting underneath the shelf; for instance, this would not be possible if the 110 shelf were of an abnormal thickness, beyond the range of the adjustment of the clamping flanges. To render the device adapted for use in such cases, I provide a sliding member 17, with rearwardly projecting sharp 115 points 38, 39, extending under the flange 34 at a certain distance therefrom; the device can then be used in the manner illustrated in Fig. 8 where the lower surface of flange 34 rests on top of the shelf or case and points 120 38, 39 are forced through the front surface of the shelf or case.

The device is also adapted for use on a bench or counter upon which it may be placed in an inclined position in order to 125 more effectively display the indications carried thereby. To this end, it is sufficient to move the adjustable clamping plate to its extreme outer position, in which position it is adapted to act as a prop or support 130

easel fashion in supporting the device in an inclined position on top of a counter 40 as shown in Fig. 9.

The device may be used in connection with 5 price cards of a size corresponding to the housing therefor, provided by the device or else the desired combinations of numbers and other indications may be obtained by using sectional cards, as shown for instance in 10 Fig. 7.

In the same it will be seen that the indication 12¢ lb. is obtained by using two main price cards 41, 42, arranged side by side to form the numeral 12, and two additional 15 smaller cards 43, 44 at the right side, one at the top and one at the bottom, providing the indications ¢ and lb. showing through openings 31, 32, respectively.

In this manner great flexibility is obtained 20 in the price marking system because with a relatively limited number of cards it is possible to form all the desired combinations. If preferred, it is, of course, possible to print the indications showing 25 through openings 31, 32, on a single card, the length of which corresponds to the combined length of cards 43, 44.

From the foregoing, it will be seen that I provide a device of a relatively simple 20 construction, which may be produced at low cost, and which will effectively serve the purposes for which it is designed. The openings through the front part of cover 15 may, of course, be arranged in a manner 35 different from that shown, and other minor details may similarly be modified without substantially departing from the inventive idea; accordingly, the drawings are to be understood as being intended for illustrative 40 purposes only and not in a limiting sense. Therefore, I reserve myself the right to carry my invention into practice in any way or manner which may enter fairly into the scope of the appended claims.

45 I claim:

1. In a card holder of the character specified, a body member having portions of three of its edges bent forwardly and inwardly to provide retaining flanges spaced from said 50 body member to receive and retain display cards inserted between said flanges and said body member, said body member having furthermore portions of two opposite edges bent rearwardly and inwardly to provide flanges spaced from the rear surface of said body member, a stationary clamping member rearwardly extending from said body member, an additional clamping member also carried by said body member and rearwardly extending therefrom adjustably mounted between said spaced flanges and the surface of said body member, and means for locking said adjustable clamping member in position.

60 2. In a card holder of the character speci-

fied, a body member having portions of three of its edges bent forwardly and inwardly to provide retaining flanges spaced from said body member to receive and retain display cards inserted between said flanges and said body member, said body member having furthermore portions of two opposite edges bent rearwardly and inwardly to provide flanges spaced from the rear surface of said body member, a stationary 70 clamping member rearwardly extending from said body member, an additional clamping member also carried by said body member and rearwardly extending therefrom adjustably mounted between said 80 spaced flanges and the surface of said body member, and a cam member carried by said adjustable clamping member adapted to lock said clamping member in position.

3. In a card holder of the character specified, the combination, with supporting means, of a body member having two opposite edges bent forwardly and inwardly to provide front retaining flanges spaced from said body member to receive and retain display 90 cards inserted between said flanges and said body member, said body member, furthermore, having a third edge partly bent forwardly and inwardly on a plane with said flanges and partly bent rearwardly and inwardly to provide a flange spaced from the rear surface of said body member, and the edge opposite thereto being bent rearwardly and inwardly to provide another flange spaced from the rear surface of said body 100 member, and a front member slidably inserted between said front flanges and the surface of said body member in superimposed relation to said cards having openings through which indications carried by 105 said cards may be displayed, said front member having a portion of one of its edges embossed to complete the frame effect of the forwardly and inwardly bent portions of the third edge of said body member, and having 110 its opposite edge embossed along its entire length to complete the frame effect of said flanges.

4. In a card holder of the character specified, the combination, with supporting means, of a body member having two opposite edges bent forwardly and inwardly to provide front retaining flanges spaced from said body member to receive and retain display 115 cards inserted between said flanges and said body member, the third edge of said body member having its end portions bent forwardly and inwardly on a level with said flanges and having its central portion bent rearwardly and inwardly to provide a flange spaced from the rear surface of said body member, and the edge opposite thereto being bent rearwardly and inwardly to provide another flange spaced from the rear surface 120 of said body member, and a front member 125

slidably inserted between said front flanges and the surface of said body member in superimposed relation to said cards, having openings through which indications carried by said cards may be displayed, said front member having the central portion of one of its edges embossed to complete the frame

effect of the forwardly and inwardly bent portions of the third edge of said body member, and having its opposite edge embossed along its entire length to complete the frame effect of said flanges. ¹⁰

ANTHONY AQUILA.
